UNITED STATES PATENT OFFICE.

EDWARD VIEIRA, OF BROOKLYN, NEW YORK, ASSIGNOR TO ROBERT GAIR COMPANY, OF NEW YORK, N. Y., A CORPORATION OF NEW YORK.

THREE-FACE SINGLE-BLANK-DISPLAY CONTAINER.

Application filed November 4, 1922. Serial No. 599,062.

To all whom it may concern:

Be it known that I, EDWARD VIEIRA, a citizen of the United States, residing in Brooklyn, in the county of Kings and State 5 of New York, have invented certain new and useful Improvements in Three-Face Single-Bank-Display Containers, of which the following is a specification.

The present invention relates to cartons or 10 containers formed by folding a blank, and particularly to display cartons or containers, and one object is to provide a carton or container comprising an inner or goods receptacle and an outer or enclosing receptacle for 15 the inner receptacle when the carton is in assembled form, the outer receptacle having a portion which provides a cover for the inner receptacle and which is convertible into a display face or display panel.

20 Another object is to provide a carton or container comprising an inner or goods receptacle and an outer or enclosing receptacle for the inner receptacle when the carton is in assembled form, the outer receptacle having a portion which provides a cover for the inner receptacle and which is convertible into a display face or display panel having an extended display tab.

25 Another object is to provide a carton or container comprising an inner or goods receptacle, and an outer or enclosing receptacle for the inner receptacle when the carton is in assembled form, the outer receptacle having a covering portion which is convertible into a display face or display panel, the display panel being maintained in an inclined display position by cooperation of a portion of the covering portion and one end of the outer receptacle for forming an easel back or rest for the display panel.

30 I attain these objects by the invention one embodiment of which is described by way of example in the subjoined specification and shown in the accompanying drawings in 35 which Figure 1, is a view, in extension, of the blank from which the carton is formed.

40 Figure 2, is a perspective view of the carton in assembled form, the display panel being in display position.

45 Figure 3, is a sectional view on the line 3—3 of Fig. 2, looking in the direction of the adjacent section-arrows.

50 Figure 4, is a sectional view on the line 4—4 of Fig. 2, looking in the direction of the adjacent section-arrows.

55 Figure 5, is a perspective view of the carton in partially assembled folded form, the inner receptacle being inverted prior to reception in the outer receptacle, and

60 Figure 6, is a perspective view of the inner and outer receptacles in assembled folded form, the covering portion being partially folded for providing either by extension thereof the cover for the inner receptacle, or by further folding a display panel 65 having an easel-back or rest.

Similar reference characters denote similar parts throughout the several views.

Referring to Fig. 5, the carton, which is made of cardboard or other suitable foldable 70 material, comprises the inner receptacle generally denoted by A, the outer receptacle generally denoted by B and the covering portion generally denoted by C.

The inner receptacle A comprises the bottom 10, the sides 11 and 12, and the ends 13 and 14.

The outer receptacle B comprises the bottom 15, the sides 16 and 17, the free hanging end-filling pieces 18 and 19, the free hanging lock-tabs 20 and 21, and the ends 22 and 23; the end 14 of the inner receptacle and the end 22 of the outer receptacle constituting an intermediate connection between the inner and outer receptacles.

The covering portion C comprises the display panel 24 having the flap 25, the semi-circular tab 26 cut from and foldably connected to the display panel, and the back brace panel 27. The display panel 24 and the back brace panel 27 are extended to provide the cover for the inner receptacle when the carton is in closed assembled folded condition; the panel 27 and the end 23 of the outer receptacle constituting by folding the 85 back-brace and the base of an easel-back or rest for the display panel 24 when the carton is in open assembled folded condition and the display panel is in display position.

The carton being folded as shown in Fig. 100 5, to fully assemble it, the end-filling pieces 18 and 19 of the outer receptacle are brought into lapping relation, the end 14 of the inner receptacle is carried over the end-filling pieces 18 and 19 and the bottom 10 105 is pressed down upon the bottom 15 of the outer receptacle, the sides 11 and 12 of the inner receptacle lying adjacent and parallel to the sides 16 and 17 of the outer receptacle, the latter sides thus becoming 110

the outer sides of the carton while the end 22 of the outer receptacle becomes one of the outer ends of the carton. The lock-tabs 20 and 21 are interlocked on the outer side 5 of the end 13 of the inner receptacle, the inner receptacle thus being enclosed by the outer receptacle. The display panel 24 and the back brace panel 27 are drawn over the inner receptacle and the flap 25 is tucked 10 into the inner receptacle adjacent and parallel to the end 14 thereof, being retained therein by engagement with said end and the sides of the inner receptacle.

To arrange the display panel 24 in display position, the flap 25 is tucked between the end 13 of the inner receptacle and the lock-tabs 20 and 21 of the outer receptacle, and the back brace panel 27 is bent or folded on the line of connection to the end 20 23 of the outer receptacle, whereby the easel-back or rest shown in Figs. 2 and 3 is provided, the display panel 24 and the display tab 26 being maintained in an inclined position and having arranged thereon 25 such characteristic matter as may be desired.

To form the carton, the blank is folded on its scoring and cuts to assume the form shown in Fig. 5, and is then further folded 30 and arranged as described relative to Figs. 5 and 6.

Having thus described my invention, it should be understood that there may be modifications thereof and variations therein without departing from the spirit of the invention, or exceeding the scope of the appended claims.

What I claim and desire to protect by Letters Patent is:

40 1. In a display container formed by folding, an inner receptacle; an outer receptacle connected to the inner receptacle for receiving the inner receptacle; a covering portion; and means for connecting the covering portion to the outer receptacle; the covering portion when extended providing a closing cover for the container, and when folded providing with said means a display panel and an easel back for the display 45 panel.

50 2. In a display container formed by folding, an inner receptacle; an outer receptacle connected to the inner receptacle for receiving the inner receptacle; a covering portion; and means for connecting the covering portion to the bottom of the outer receptacle; the covering portion when extended providing a closing cover for the container, and when folded providing with said means a display panel and an easel back for the display 55 panel.

60 3. In a display container formed by folding, an inner receptacle; an outer receptacle connected to the inner receptacle by adjacent ends of the inner and outer re-

ceptacles; the inner receptacle being received in the outer receptacle; and a covering portion connected to the outer receptacle by the end of the outer receptacle opposite to the first mentioned ends; the covering portion when extended providing a closing cover for the container, and when folded providing with said opposite end a display panel and an easel back for the display panel.

75 4. In a display container formed by folding, an inner receptacle having a bottom, side walls, and end walls; an outer receptacle having a bottom, side walls and end walls; the inner and outer receptacles being 80 connected by adjacent walls of the outer and inner receptacles; the inner receptacle being received in the outer receptacle and a covering portion connected to the outer receptacle by a wall of the outer receptacle opposite 85 to said adjacent walls; the covering portion when extended providing a closing cover for the container, and when folded providing with said opposite wall a display panel and an easel back for the display panel.

90 5. In a display container formed by folding, an inner receptacle having a bottom, side walls and end walls; an outer receptacle having a bottom, side walls, end walls, end-filling pieces, and lock-tabs; the inner and outer receptacles being connected by adjacent walls of the outer and inner receptacles; the inner receptacle being received in the outer receptacle; and a covering portion connected to the outer receptacle by a wall of the outer receptacle opposite to said adjacent walls; the covering portion when extended providing a closing cover for the container, and when folded 95 providing with said opposite wall a display panel and an easel back for the display panel.

100 6. In a display container formed by folding, an inner receptacle having a bottom, side walls, and end walls; said side and end walls being separated from each other and connected to said bottom; an outer receptacle having side walls, end walls, end-filling pieces, and lock-tabs; said side and end walls being separated from each other and connected to said bottom; the inner and outer 105 receptacles being connected by adjacent end walls of the inner and outer receptacles; the inner receptacle being received in the outer receptacle; and a covering portion connected to the outer receptacle by an end wall of the outer receptacle opposite to said adjacent end walls; the covering portion when extended providing a closing cover for the container, and when folded providing with said opposite end wall a display panel and 110 an easel back for the display panel.

115 7. A blank having longitudinal and transverse scoring and cuts for folding the blank thereon to form a display container, the blank comprising an inner receptacle bot- 120

tom section, side sections and end sections for the inner receptacle, an outer receptacle bottom section, side sections and end sections for the outer receptacle, one of the end sections of the inner receptacle adjoining one of the end sections of the outer receptacle, free-hanging end-filling sections, free-hanging lock-tab sections, a back-brace section, one of the end sections of the outer receptacle adjoining the back-brace section, a display panel section, and a flap section.

8. A blank having longitudinal and transverse scoring and cuts for folding the blank thereon to form a display container, the blank having an oblong main portion with end extensions and lock-tab extensions; the main portion comprising an inner receptacle bottom section, side sections and one end section for the inner receptacle, an outer re-

ceptacle bottom section, side sections and one end section for the outer receptacle, said end sections of the inner and outer receptacles adjoining each other, and free-hanging end-filling sections; one of the end extensions of the blank comprising the other end section for the outer receptacle, a back-brace section, the last mentioned end section of the outer receptacle adjoining the back-brace section, a display panel section, and a flap section; the other of the end extensions of the blank comprising the other end section for the inner receptacle; and the lock-tab extensions comprising lock-tabs having interlocking heads.

EDWARD VIEIRA.
